SLIDING DOOR

William J. Nolan, Woodmere, N.Y.

Application October 18, 1957, Serial No. 690,955

3 Claims. (Cl. 20—19)

This invention relates to a door construction, and more particularly to a sliding door assembly.

The object of the invention is to provide a sliding door construction which includes a frame that is adapted to be mounted in a recess in a wall or other structure, and wherein the sliding door unit of the present invention includes a stationary rectangular frame, there being a pair of body members slidably mounted in the frame, and wherein the sliding body members are adapted to telescope with respect to each other.

A still further object of the invention is to provide a sliding door construction which includes a unit that can be conveniently mounted in a recess or opening in a wall, and wherein the sliding door assembly of the present invention includes a pair of members which can be moved to open or closed position, said members adapted to telescope within each other, so that the door can be moved to open position when desired.

A further object of the invention is to provide a sliding door assembly which is extremely simple and inexpensive to manufacture.

Other objects and advantages will be apparent during the course of the following description.

In the accompanying drawings, forming a part of this application, and in which like numerals are used to designate like parts throughout the same.

Figure 1 is an elevational view illustrating the sliding door assembly of the present invention, showing the molding on the frame, and showing the members in open position.

Figure 2 is an enlarged elevational view showing the sliding door unit per se.

Figure 3 is a sectional view taken on the line 3—3 of Figure 2.

Figure 4 is a side elevational view of the first body member or sliding door member, and with parts broken away and in section.

Figure 5 is a side elevational view of the other sliding body member.

Figure 6 is a sectional view taken on the line 6—6 of Figure 4.

Figure 7 is a sectional view taken on the line 7—7 of Figure 5.

Figure 8 is an end elevational view taken through the assembly, and with parts broken away and in section.

Referring in detail to the drawings, there is shown a sliding door construction which includes a rectangular open frame that is indicated generally by the numeral 10, and the frame 10 is adapted to be mounted in an opening or recess in a supporting structure such as the wall 11. The frame 10 includes a horizontally disposed upper I-beam 12 which defines an upper rail for a purpose to be later described. The frame 10 further includes a lower horizontally disposed base 13 which is provided with an elongated channel 14 therein, Figure 3. As shown in the drawings, the frame 10 further comprises spaced parallel vertically disposed end pieces 15 and 16. Extending inwardly from the upper portion of the end piece

2

15 and secured thereto in any suitable manner is a pair of horizontally disposed L-shaped beams 17.

Slidably mounted in the frame 10 are first and second body members 18 and 19, Figures 4 and 5. The numeral 5 20 indicates molding or trim which can be arranged adjacent the outer surface of the unit so as to enhance or increase the attractiveness of the apparatus or device.

As shown in Figure 6, the first body member 18 includes a horizontally disposed bottom wall 21 which is 10 provided with a tongue 22 that is adapted to slidably engage the channel 14 in the base 13. The tongue 22 defines therein a groove 23. The body member 18, which is hollow, further includes spaced parallel vertically disposed side walls 24 and an end wall 25. The top and one 15 end of the body member 18 is open whereby the other body member 19 can move into and out of the body member 18.

Connected to the upper ends of the side walls 24 are 20 brackets 26, and journaled in the brackets 26 are outer rollers 27 and inner rollers 28. The outer rollers 27 are adapted to engage the beams 17, as for example as shown in Figure 8.

As shown in Figure 7, the second body member 19 is 25 smaller in cross section than the first body member 18 which is shown in Figure 6, and the second body member 19 includes a bottom member 30 which has a finger 31 depending therefrom, and the finger 31 engages the groove 23 which is defined by the arcuate tongue 22. The body member 19 further includes spaced parallel vertically disposed side members 29 and a top member 32. The top member 32 of the body member 19 is provided with a 30 pair of spaced parallel elongated recesses 33 which are adapted to be engaged by the inner rollers 28. Extending upwardly from the top member 32 of the second body member 19, is a pair of spaced apart support members, and rollers 35 are connected to each support member 34, the rollers 35 engaging the rail 12. As shown in Figure 2, the numeral 36 indicates a stop lip which is adapted to be used for limiting sliding movements of 35 the parts in one direction. As shown in Figure 1 for example, the beam or rail 12 may be anchored in place by suitable securing elements such as the screws 37.

From the foregoing, it is apparent that there has been 40 provided a sliding door construction which is in the nature of a unit that is self-contained and which can be mounted in a suitable supporting structure such as the wall 11. In use, the frame 10 is adapted to be mounted in a wall such as the wall 11 which may form part of a store, home, or other building or locality. The body member 18 is hollow and has one end open and this construction permits the other body member 19 to telescope therewith whereby when a person or object is to be moved through the doorway opening, the body member 19 can be moved entirely or partially into the other body member 18 so as to provide sufficient clearance through the door frame 10.

The pair of body members 18 and 19 are both slidably mounted in the frame so that by moving the body members 18 and 19 to their extended position, the space defined within the molding 20 can be closed off. It is to be noted that the rectangular molding 20 defines or encloses an area which is less than the area of the rectangular frame 10 and by properly extending the body members 18 and 19, the entire area within the molding 20 can 45 be blocked off. Similarly, the body member 19 can be moved into the body member 18, and then these body members can both be moved to an out-of-the-way position as shown in Figure 1 for example whereby the space within the molding or trim 20 is open so that persons can 50 readily gain access or pass through the space within the molding 20. In view of the fact that the area within the molding 20 is of less size than the area within the frame

10, it will be seen that space is provided for receiving the body members 18 and 19 as shown in Figure 1, as for example when the sliding door unit is in open position.

The pair of beams 17 are engaged by the rollers 27 so that the body member 18 is free to slide back and forth. Similarly, the tongue 22 on the lower end of the body member 18 engages the channels 14 in the base 13 and this arrangement provides a guide for the body member 18 as the body member 18 moves back and forth. The inner rollers 28 are adapted to engage the recesses 33 in the top of the body member 19 so as to insure that the body members can telescope with a minimum amount of friction. The inner body member 19 has the finger 31 which engages groove 23 and this serves to insure that the body members 18 and 19 will be maintained in their proper aligned position as they are moved back and forth. The body member 19 has the support members 34 extending upwardly therefrom, and the rollers 35 are carried by the support members 34, the rollers 35 engaging the lower portion of the rail or beam 12, as shown in Figures 2 and 8 for example.

The parts can be made of any suitable material and in different shapes or sizes.

The sliding door unit of the present invention may be distributed or sold as a package unit so that it can be readily mounted in a wall recess. The device may be finished with suitable trim or molding as desired. The sliding door unit includes the prefabricated body members or doors 18 and 19. The lip 36 acts as a stop member to limit movements of the body member 18 in one direction, as for example in order to limit movement of the body member 18 from right to left in Figure 2.

The sliding door assembly of the present invention can be used in areas where space is at a premium, and the unit can be quickly and inexpensively and easily installed and the unit may be installed or mounted as a permanent unit in different types of buildings such as hotels, hospitals, homes or the like. The unit may be finished in wood veneers if desired. The device may be made so that it is vermin proof, and dust proof as well as warp proof, so that it is especially suitable for use in closest installations, and the door will also help minimize fire hazards. The pair of body members are adapted to be moved by hand, that is the members are slid or moved back and forth manually.

Minor changes in shape, size and rearrangement of details coming within the field of invention claimed may be resorted to in actual practice, if desired.

I claim:

1. In a sliding door construction, a rectangular open frame including a horizontally disposed I-beam defining an upper rail, said frame further including a horizontally disposed base provided with a longitudinally extending channel therein, first and second spaced parallel vertically disposed end pieces extending between said rail and base and secured thereto, a pair of horizontally disposed L-shaped beams extending inwardly from the upper portion of said first end piece and secured thereto, first and second body members movably mounted in said frame, said first body member being hollow and comprising a horizontally disposed bottom wall provided with a tongue for engage-

ment with the channel in said base, said tongue defining a groove therein, said first body member further including a pair of spaced parallel vertically disposed side walls and a vertically disposed end wall, the top and one end 5 of said first body member being open, brackets secured to the upper ends of said side walls, inner and outer rollers supported by said brackets, said outer rollers engaging said beams, said second body member being smaller in cross section than said first body member, said 10 second body member being mounted for telescoping movement into and out of said first body member, said second body member comprising a bottom member having a depending finger for engagement with the groove in said first body member, said second body member 15 further including spaced parallel vertically disposed side members and a top member, there being spaced parallel recesses in the top member of said second body member for engagement by said inner rollers, support members extending upwardly from the top of said second body member, and rollers connected to said support members for 20 engagement with said upper rail.

2. In a sliding door construction, a rectangular open frame including a horizontally disposed I-beam defining an upper rail, said frame further including a base provided with a longitudinally extending channel therein, spaced parallel vertically disposed end pieces extending between said rail and base and secured thereto, a pair of L-shaped beams extending inwardly from the upper portion of said first end piece and secured thereto, first 25 and second body members movably mounted in said frame, said first body member being hollow and comprising a horizontally disposed bottom wall provided with a tongue for engagement with the channel in said base, said tongue defining a groove therein, said first body member further including a pair of spaced parallel vertically disposed side walls and a vertically disposed end wall, the top and one end of said first body member being open, brackets secured to the upper ends of said side walls, inner and outer rollers supported by said brackets, 30 said outer rollers engaging said beams, said second body member being smaller in cross section than said first body member, said second body member being mounted for telescoping movement into and out of said first body member.

3. In a sliding door constructed as in claim 2, wherein said second body member comprising a bottom member having a depending finger for engagement with the groove in said first body member, said second body member further including spaced parallel vertically disposed side 35 members and a top member, there being spaced parallel recesses in the top member of said second body member for engagement by said inner rollers, support members extending upwardly from the top of said second body member, and rollers connected to said support members 40 for engagement with said upper rail.
